UNITED STATES PATENT OFFICE.

ERNEST SCHOENHEIT, OF PITTSBURGH, PENNSYLVANIA.

SASH-HOLDER.

1,147,270.

Specification of Letters Patent. Patented July 20, 1915.

Application filed March 7, 1913. Serial No. 752,577.

To all whom it may concern:

Be it known that I, ERNEST SCHOENHEIT, a citizen of the United States, residing at Pittsburgh, in the county of Allegheny, in the 5 State of Pennsylvania, have invented certain new and useful Improvements in Sash-Holders, of which the following is a specification.

This invention relates to improvements in 10 sash holders.

The invention consists more particularly in the provision of a rotary spiral shaft disposed in the channeled side of the window sash, one end of said shaft being beveled 15 and disposed in a cup-shaped bearing associated with the recessed window sash and secured to the casing, or this end of the shaft may be of hollow formation adapted to receive and rotate upon a beveled projection disposed upon said bearing; the opposite end of the spiral shaft being journaled in a cup-shaped ball bearing disposed in the channeled sash and secured to the casing. When the window is raised said shaft is 20 pressed against and rotates upon the balls of the ball bearing, but when the window is lowered friction of the shaft in its other bearing offers sufficient resistance to off-set the weight of the window and, with outside 25 pressure removed, to stop its descent.

This invention consists in the combination and arrangement of parts to be hereinafter fully described in the following specification, pointed out in the claims and illustrated in the accompanying drawings which form a part of the specification and in which—

Figure 1 is a front elevation, partly in section, of a window embodying my improvements. Fig. 2 is a section taken on line 40 2—2 of Fig. 1. Fig. 3 illustrates a modification of the lower shaft bearing. Fig. 4 is a further modification of the same member. Fig. 5 is a plan of Fig. 3. Fig. 6 is a 45 plan of the base of Fig. 4 and is taken on line 4—4 of that figure. Fig. 7 is a section taken on line 7—7 of Fig. 1. Fig. 8 is a section taken on line 8—8 of Fig. 1.

Like reference characters indicate corresponding parts throughout the several views.

1 is the window sash, one side of which is 50 channelled longitudinally as at 2 and this portion is formed near its lower extremity with integral nuts 3, 3 adapted to ride in 55 the spiral groove of the rotary shaft 4; said shaft being disposed in and extending

longitudinally of the apertured portion of said window sash. The base of the shaft 4 in its preferred form is beveled as at 5, said beveled portion terminating in an extremity 6 of cylindrical shape and said beveled and cylindrical portion being seated in a cup-like bearing 7 formed with a central aperture adapted to receive the said portions. One corner of the apertured side of the 65 sash being cut away to permit the insertion of said cup-like bearing which is secured by screws 8 to the window casing 9.

The upper termination of the shaft 4 is cylindrical in formation and is disposed in 70 a cup-shaped bearing 10 secured by screws 11 to the window casing 9 and said cylindrical shaft termination is hollowed out to receive one of the balls 12 upon which said shaft rotates, the other ball 12 being disposed in a recess in the bearing 10 and in frictional contact with the first mentioned ball 12.

In Fig. 3 a modification of the lower shaft bearing is illustrated. The bearing 7 is 80 provided with a projection 13, the base of which is beveled and the stem of which is of cylindrical formation; the base of shaft 4 being apertured to receive said projection upon which it rotates and said shaft base 85 being grooved for engagement with the nuts 3, 3 of the window frame. Fig. 4 is a further modification of this bearing which comprises an apertured disk-like portion 14 secured to the window sill and another disk-like member 15 is disposed upon the member 14 and formed integral with a shaft 16 projected into the hollowed extremity of shaft 4 and into the channeled bearing 14. Formation of the shaft 4 and member 15 is such 90 that rotation of the former will rotate the latter upon the bearing 14 producing sufficient friction to stop the descent, through gravity, of the window.

What is claimed is:—

1. The combination with a channeled window sash, of a spirally grooved rotary shaft disposed in the channeled portion thereof, an upper anti-friction bearing for said shaft, a lower friction bearing for said shaft and 105 a nut formed in the channeled portion of said window sash and adapted to travel in the spirally grooved portion of said shaft as the window sash is raised or lowered.

2. The combination with a window sash, 110 of a rotary shaft, an upper anti-friction bearing for said shaft associated with the

window casing, a lower friction bearing for said shaft associated with the window casing and means carried by said window sash and operatively associated with said shaft 5 for actuating the same as the window sash is raised or lowered in the casing.

In testimony that I claim the foregoing as

my own I have hereto affixed my signature in the presence of two subscribing witnesses.

ERNEST SCHOENHEIT.
